(57) **CLAIM**

The ornamental design for a toy baseball hitting device, as shown and described.

DESCRIPTION

FIG. 1 is a perspective view of a toy baseball hitting device, showing my new design in an assembled configuration; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is an exploded perspective view of the toy baseball hitting device of FIG. 1 showing the manner of assembly; FIG. 9 is a front elevational exploded view thereof; FIG. 10 is a rear elevational exploded view thereof; FIG. 11 is a left side exploded elevation view thereof; FIG. 12 is a right side exploded elevation view thereof; FIG. 13 is a top plan exploded view thereof; and, FIG. 14 is a bottom plan exploded view thereof. The broken lines in the Figures represent portions of the article that form no part of the claimed design.

1 Claim, 14 Drawing Sheets
